Attorneys

UNITED STATES PATENT OFFICE.

GEORGE F. KEY, OF DETROIT, MICHIGAN.

ROTARY FEEDER.

Application filed June 6, 1923. Serial No. 643,663.

To all whom it may concern:

Be it known that I, GEORGE F. KEY, a citizen of the United States of America, residing at Detroit, in the county of Wayne and State of Michigan, have invented certain new and useful Improvements in Rotary Feeders, of which the following is a specification, reference being had therein to the accompanying drawings.

10 This invention relates to devices for distributing, measuring and handling finely comminuted or powdered material such as Portland cement, grain, powdered coal, etc., and refers more particularly to an apparatus 15 designed primarily for use in connection with stokers for furnaces and the like wherein pulverized fuel is used.

An object of the invention is to provide a practical and efficient apparatus which is 20 preferably provided with means for selecting and measuring accurately and definitely the fuel supplied thereto and which is also preferably provided with means for delivering constantly and steadily the measured 25 fuel to the stoker.

Another object is to provide an apparatus in which the measuring device is preferably spaced from the supply conduit leading 30 from the storage tank and is preferably located in a casing that extends downwardly from the supply conduit so that a free gravity head is provided on the fuel in the casing.

Another object is to provide simple and 35 effective means for removing any overflow from the casing enclosing the measuring device and for returning the surplus fuel to the source of supply.

Another object is to provide a measuring 40 device that is simple in construction and that is preferably provided with means for feeding the fuel intermittently and in constant quantity to a conduit leading to the stoker.

45 Another object is to provide simple and effective means for preventing the escape of any material or dust from the casing which encloses the measuring device.

50 With the above and other objects in view, the invention consists of certain novel features of construction, combinations, and arrangements of parts as will be more fully de-

scribed and particularly pointed out in the appended claims.

In the accompanying drawings:— 55

Figure 1 is a side elevation of an apparatus embodying my invention and showing parts in section;

Figure 2 is a sectional view taken on line 2—2 of Figure 1; 60

Figure 3 is a front elevation of the construction shown in Figure 2.

With the present invention, the comminuted material is preferably maintained in a circuit that is preferably composed of a 65 suitable storage tank, a chute, an elevator, and a conveyor, the latter preferably having a proper outlet or take-off opening for deflecting the material to be used to a measuring device that is preferably constructed 70

to determine the required volume or desired weight for any definite purpose. The unused material preferably continues in the circuit through the conveyor, chute and elevator, the latter leading back to the storage 75

tank from which the material is started. By a simple arrangement in the shape of the storage tank, I have practically reduced to a minimum the bridging of the material over the conveyor in the tank outlet. By removing 80

any change of head in the material over the measuring device. Also this same scheme renders any "flooding" harmless for the reason that the excess thus caused is carried 85

along as unused material in the circuit and is passed on to the next take-off (should more than one be employed) or is carried still further back to the storage tank. Furthermore, all of the tubes are essentially 90

made dust-proof so that the apparatus is not a menace to health. It will also be noted that the measuring device eliminates all irregularities of feed and gives a constant and uniform supply in the required time and in the proper place. Thus, I have overcome 95

in a thoroughly practical way all of the obstacles which are encountered, not only in the handling, but in the measuring of the quantity of material used. As a result, I 100 have provided a positive means of determining the rate and amount of delivery at any instant or in any specified time at a fixed or definite place.

Referring now to the drawings in which like characters of reference designate corresponding parts throughout the several views, the numeral 1 designates a tube or casing 5 leading from a suitable tank or storage receptacle 2 to a downwardly extending chute 3 which is connected at its lower end to an upwardly inclined tube 4 leading back to the tank 2. The bottom of the tube 1, adjacent to the chute 3, is preferably provided with a suitable opening 5 through which the material in the tube may fall by gravity into a casing 6 that forms a housing for a measuring device 7.

15 The casing 6 is preferably cylindrical in shape and at diametrically opposite points thereof is preferably provided with rectangular extensions 8 and 9 respectively, the extension 8 having lateral flanges 10 at its upper end secured to substantially L-shaped flanges 11 extending downwardly from the tube 1.

20 The material discharged from the storage tank is preferably moved along in the tube 1 to the opening 5 by means of a screw conveyor 11' having spaced flights 12 arranged thereon between the tank and the opening 5. The conveyor is preferably devoid of flights over the major portion of the opening 5 and is preferably provided with one or more flights 13 between the opening 5 and the chute 3 for removing any overflow from the casing 6. This overflow is discharged from the tube 1 into the chute 3, from the lower end of which it is returned to the tank 2 by means of a suitable elevator 14 in the upwardly inclined tube 4.

25 The measuring device 7 preferably consists of a rotatable wheel 15 which is preferably keyed to a horizontal shaft 16 journaled in a pair of spiders 17 secured to the opposite open ends of the casing 6. The shaft may be driven by any suitable means, but is preferably driven by means of a variable speed motor. The wheel 15 is preferably located midway between the spiders 17 and is preferably provided with a relatively wide rim 18 that has a series of spaced relatively narrow elongated pockets 18' formed in the periphery thereof. These pockets are preferably of a length equal to the width of the extension 8 and are adapted to receive the material therefrom. Upon rotation of the wheel, the contents of the pockets will fall through the extension 9 and into a spout 19 which is secured to the extension 9 and which discharges into a suitable pipe or delivery conduit 20 leading to a stoker or the like (not shown). The forward wall 21 of the spout is preferably inclined as shown while the rear wall 22 is preferably vertical.

30 Should air under pressure be used to move the material through the conduit 20, I preferably provide an opening 23 in the

inclined wall 21 of the spout to permit air from the atmosphere to mix with the material passing downwardly through the spout to break up any eddies that may occur as a result of the air in the conduit 20 striking against the rear wall 22 of the spout. The quantity of air admitted through the opening 23 is preferably regulated by means of a closure 24 that is preferably pivotally mounted at its upper end on a rod 25 extending through the sides of the spout. The closure is preferably constructed of yieldable material and the sides thereof frictionally engage the edges of the opening to retain the closure in adjusted position. The spout is preferably provided with a suitable handle 26 for adjusting the same in the opening.

35 To prevent the escape of material or dust, etc., from between the wheel rim 18 and the casing 6, I preferably provide a pair of compressible rings 27 that are disposed upon opposite sides of the wheel and that engage the sides of the wheel rim 18 and abut against parallel flanges 28 extending inwardly from the inner walls of the casing 6. Annular followers 29 bear against the rings 27 and are preferably held in position by means of suitable springs 30 which are located between the followers and the spiders 17. The followers are adapted to be adjusted by means of bolts 31 that extend outwardly through the spiders 17.

40 For preventing any material other than the material in the pockets 18' from passing down into the spout 19, I preferably provide a pair of rubbing blocks 32 that bear against the periphery of the wheel rim 18. These blocks are preferably slidably mounted in guides 33 formed upon diametrically opposite sides of the casing 6 and are normally retained in engagement with the wheel 15 by means of springs 34 that are disposed between the outer edges of the blocks and a pair of equalizing bars 35 that are threaded upon spaced bolts 36 adjustably mounted in the outer walls of the casing 6 at the ends of the blocks.

45 For preventing the escape of material or dust, etc., from between the blocks 32 and the edges of the openings 37 in the casing, I preferably provide a pair of compressible pads 38 which rest upon the blocks 32 at the inner ends thereof. These pads are preferably located in guides 39 formed in the casing above the guides 33, the inner walls of the casing being preferably inclined inwardly as shown at 40 to form the inner walls of the guides 39. The pads 38 are preferably adjusted by means of bolts 41 that are threaded through a pair of plates 42 detachably secured to the outer walls of the casing 6.

50 In use, the portion of the material that is taken off from the tube 1 enters the

pockets 18' in the measuring wheel and is discharged therefrom into the spout 19 from which it is delivered in a constant volumetric quantity into the conduit 20 leading to the stoker. The rings 27 and pads 38 prevent any escape of material or dust en route through the casing, consequently, the material passes from the extension 8 to the spout 19 by means of the pockets 18' only. Thus, a positive volumetric measurement is secured.

I preferably arrange the measuring wheel 7 with respect to the conveyor 1 so that the distance from the crown of the said wheel to the opening 5 is less than the altitude of the cone of repose of the material on the measuring wheel. By such an arrangement arching of the material and subsequent improper feeding of the material to the said wheel is prevented, a constant gravity head on the feed wheel being maintained.

Although I have shown and described only one storage tank and one measuring device, it is apparent that any number of either or both may be readily used by merely employing additional conveyors, chutes, etc., similar to those described herein.

While it is believed that from the foregoing description, the nature and advantages of the invention will be readily apparent I desire to have it understood that I do not limit myself to what is herein shown and described and that such changes may be resorted to when desired as fall within the scope of what is claimed.

What I claim as my invention is:—

1. In an apparatus of the class described, the combination with a storage tank containing comminuted material, of a tube leading from the tank and having a takeoff opening therein, a casing secured to the tube about the opening, a member communicating with said tube, a conveyor in the tube having blades upon one side of the opening for moving the material from the tank to the casing, a delivery conduit, means in the casing for transferring the material in measured quantities from the casing to the conduit, said conveyor also having one or more blades upon the opposite side of the opening in said tube for moving any overflow from the casing into the member aforesaid, and means for returning to the tank the material received by said member.

2. In an apparatus of the class described, the combination with a storage tank containing comminuted material, of a tube leading from the tank, a casing in communication with the tube, a conveyor in the tube for moving the material from the tank to the casing, a delivery conduit, a wheel in the casing and pockets in the rim thereof for transferring the material in measured quantities from the casing to the delivery conduit, compressible members engaging the

casing and rim of said wheel for preventing the escape of material therebetween, followers bearing against said members, and means for adjusting said followers to vary the compression of said members.

3. In an apparatus of the class described, the combination with a storage tank containing comminuted material, of a tube leading from the tank, a casing in communication with the tube, a conveyor in the tube for moving the material from the tank to the casing, a delivery conduit, a wheel in the casing and pockets in the rim thereof for transferring the material in measured quantities from the casing to the delivery conduit, compressible members engaging the casing and the rim of the wheel for preventing the escape of material therebetween, and followers yieldably pressed against said members for retaining the same in position.

4. In an apparatus of the class described, the combination with a storage tank containing comminuted material, of a tube leading from the tank, a casing in communication with the tube, a conveyor in the tube for moving the material from the tank to the casing, a delivery conduit, a wheel in the casing having pockets in the rim thereof for transferring the material in measured quantities from the casing to the delivery conduit, blocks pressed against the rim of said wheel for preventing any material other than that in said pockets from being transferred, and means for adjusting said blocks.

5. In an apparatus of the class described, the combination with a storage tank containing comminuted material, of a casing, means for conveying material from the tank to said casing, a delivery conduit, a wheel in the casing having pockets in the rim thereof for transferring the material in measured quantities from the casing to said conduit, blocks engaging the rim of said wheel for preventing any material other than that in said pockets from being transferred, and means for preventing the escape of material from between said blocks and said casing.

6. In an apparatus of the class described, the combination with a storage tank containing comminuted material, of a casing, means for conveying material from the tank to said casing, a delivery conduit, a wheel in the casing having pockets in the rim thereof for transferring the material in measured quantities from the casing to said conduit, blocks engaging the rim of said wheel for preventing any material other than that in said pockets from being transferred, and adjustable pads for preventing the escape of material from between said blocks and said casing.

7. In an apparatus of the class described, the combination with a storage tank containing comminuted material, of a conveyor for continuously conveying material from the

- 5 tank, said conveyor having an outlet intermediate its ends, a casing adapted to receive material from the conveyor outlet, a delivery conduit, means for transferring the material in measured quantities from the casing to the conduit, said means adapted to transfer selectively varying quantities of material in a given time, the capacity of said conveyor being such that the said casing is at all times substantially filled with the material from the conveyor outlet, and means for removing excess material from a point of the conveyor beyond said outlet.
- 10 8. In an apparatus of the class described, the combination with a storage tank containing comminuted material, of a conveyor for continuously conveying material from said storage tank, said conveyor having an outlet at a point intermediate its ends, a casing positioned below the conveyor outlet and adapted to receive material therefrom in variable amounts for maintaining substantially a predetermined fixed quantity of the material within said casing, a delivery conduit, means for transferring the material from said casing to said conduit in measured quantities, said means being adapted to be operated to vary the rate of delivery of the said material from the casing to said conduit, and means for removing the material not passing through said outlet from the said conveyor at a point beyond said outlet.
- 15 9. In an apparatus of the class described, the combination with a storage tank containing comminuted material, of a conveyor for continuously conveying material from the tank, said conveyor having an outlet intermediate its ends, a casing positioned below the conveyor outlet and adapted to receive material therefrom, a delivery conduit, a measuring device within said casing for transferring material in measured quantities from said casing to said conduit, said conveyor being adapted to be operated at varying speeds for supplying varying amounts of material from said conveyor to said casing for maintaining a substantially constant head on said measuring device, and

means for returning to the storage tank the excess material from the conveyor at a point beyond said outlet.

10 10. In an apparatus of the class described, the combination with a storage tank containing comminuted material, of a conveyor for continuously conveying material from the tank, said conveyor having an outlet intermediate its ends, a casing positioned below the conveyor outlet and adapted to receive material therefrom, a delivery conduit, a shaft, a rotatable measuring device mounted on said shaft, the speed of rotation of said shaft being regulable for delivering material in varying measured quantities from said casing to said conduit, said conveyor being adapted for supplying varying amounts of material from said conveyor to said casing for maintaining a substantially constant head on said measuring wheel, and means for removing the excess material passing beyond said outlet from said conveyor and returning such excess material to the storage tank.

15 11. In an apparatus of the class described, the combination with a storage tank, containing comminuted material, of a conveyor for continuously conveying material from the tank, said conveyor having an outlet, a casing below the conveyor adapted to receive material from the conveyor outlet, a rotatable measuring wheel within the casing for transferring material in measured quantities from said casing to a point therebelow, said casing having a portion between the measuring wheel and the conveyor outlet for receiving the material from the said conveyor in sufficient amount for maintaining a constant gravity head on the measuring wheel, the distance from the crown of the measuring wheel to the conveyor opening being less than the altitude of the cone of repose of the material on the measuring wheel to maintain said constant gravity head on the feed wheel and to prevent arching of the material on the wheel.

In testimony whereof I affix my signature.
GEORGE F. KEY.
